UNITED STATES PATENT OFFICE.

GEORGE B. MORDEN, OF SEATTLE, WASHINGTON.

AUTOMOBILE-HEATER.

1,295,562.

Specification of Letters Patent. Patented Feb. 25, 1919.

Application filed December 14, 1917. Serial No. 207,189.

To all whom it may concern:

Be it known that I, GEORGE B. MORDEN, a citizen of the United States, residing at Seattle, in the county of King and State of Washington, have invented certain new and useful Improvements in Automobile-Heaters, of which the following is a specification.

This invention relates to automobiles or the like.

10 The main object of my invention is the provision of simple and inexpensively constructed means for utilizing the heat of an automobile engine's exhaust gases for heating purposes. A further object is the provision of a heater which will effectually serve as a muffler.

The invention consists in the novel construction, adaptation and combination of parts, as will be hereinafter described and 20 claimed.

In the accompanying drawings, Figure 1 is a plan view of apparatus embodying the present invention, parts being broken away to disclose the interior of the radiator member. Fig. 2 is a transverse vertical section of the apparatus shown applied. Fig. 3 is a longitudinal vertical section of the same.

Referring to the drawings, the numeral 5 designates a radiator in the form, preferably, of a rectangular box having a removable cover 6 which is secured to the radiator body as by screws 7. Extending into the front of said radiator and adjacent to one of its sides is a pipe 8 forming a branch of 30 a pipe 9 through which is exhausted the gaseous combustion products of an automobile engine, not shown.

The branch 8 and a second branch 10 are connected to the exhaust pipe 9 by a casing 40 11 of a three-way valve 12. Said valve is pivotally connected to a crank arm 13 whereby the valve is regulated, as by means of a pedal attachment 14, to direct the exhaust gases selectively through the branch 8 into the radiator or through the branch 10 to the external atmosphere at the rear of the car.

At or near the diagonally opposite corner of the radiator from its connection with the 50 branch 8 is an outlet pipe 15 opening into the atmosphere at the rear of the car.

Provided within the radiator are diagonally disposed baffle plates 16 and 17 arranged substantially as illustrated in Fig. 1, 55 that is to say—the baffle 16 is located to

have one of its ends 16¹ at a short distance from and in a vertical plane extending through the projected axis of the branch 8. The other end 16² of this baffle terminates within a short distance from and intermediate of the length of the baffle 17 which, as shown, is arranged in angular relation with respect to baffle 16. By such an arrangement of baffles the gases emitted into the radiator are divided by the end of baffle 16 into two currents, one of which is deflected by the baffle face 16² against the face 17¹ of the other baffle 17, whence it is deflected and directed as indicated by arrow *x* (Fig. 1) into the space back of baffle 17 to 70 escape by pipe 15. The other of the referred-to currents from the branch 8 passes through the space back of the baffle 16 and thence, as indicated by arrow *y*, joins the first mentioned current at the outlet 15. 75

The radiator 5 is contained in a casing 18 which is open at the top and is connected from its sides to car frame members 19 below an opening 20 in the car floor 21. Provided in said floor opening is a perforated plate 22, and between the latter and the top of the radiator is a plate 23 having a centrally disposed opening of less width and length than the radiator thereby affording deflector elements 23¹ and 23² which extend inwardly 80 from the planes of the ends and sides of the radiator, as shown in Figs. 2 and 3.

The aforesaid casing is desirably of rectangular shape and of somewhat greater dimensions than the radiator to provide air 85 spaces 24 and 24¹ beneath and about the sides and ends of the radiator, the spaces 24¹ communicating by spaces 24² below the deflector elements 23¹ and 23² with the opening of plate 23. 95

Legs 25 provided on the radiator are employed to retain the radiator in its spaced relation with the bottom 18¹ of the casing, and is held down by means of screws 26 extending through the casing bottom and longitudinally disposed channel bars 27 upon which the casing is supported. The bars 27 also receive the ends of hanger bolts 28 depending from the car floor 21. 100

26¹ and 28¹ represent nuts respectively engaging the threaded ends of the screws 26 and bolts 28.

By thus securing the radiator and the casing to the supporting bars 27, the casing may be made of relatively thin material and all 105

vibrating is obviated. 29 represents air inlet holes provided in the casing bottom 18¹ at about the midwidth thereof.

To operate the apparatus, the valve 12 is brought into the position in which it is shown in Fig. 3, thereby directing the hot gases from exhaust pipe 9 through branch 8 into the radiator 5. The stream of gases when encountering the end 16¹ of the baffle 16, is divided into two currents which, through the offices of the two baffles 16 and 17, are guided about the radiator chamber and eventually discharged through outlet pipe 15. As this occurs, air is admitted through holes 29 into the casing 18 below the radiator and thence flows through the ducts or spaces 24¹ against the underside of the deflector elements 23¹ and 23² to be deflected thereby against the top of the radiator to finally escape in a heated state through the perforated floor plate 22 to warm the interior of the car or the feet of the occupants when placed upon such plate. When the exhaust gases are caused to flow through the radiator and by reason of the circuitous paths by which it traverses the interior of the same, the noises of the escaping gases are silenced and in consequence the apparatus serves as a muffler in addition to performing the office of heating the air which passes through the casing 18.

By regulating the valve 12, the exhaust gases may be diverted into the exhaust branch pipe 10 without being muffled in the radiator as will be understood.

35

What I claim is:—

1. In apparatus of the class described, the combination with a radiator of a casing inclosing said radiator and having inlet and outlet openings respectively above and below the radiator, and deflector elements extending into the space above the radiator for causing air ascending through the casing to be directed downwardly upon the top of the radiator before escaping through the outlet opening of the casing.

40

2. In apparatus of the class described, the combination with the floor of a motor vehicle and a radiator, of a casing inclosing said radiator and provided with air inlet and outlet openings, respectively, below and above the radiator, bars supporting said casing, fastenings to secure the radiator to both the casing and to said bars, and means engaging the bars for suspending the casing and the radiator from said vehicle floor.

50

Signed at Seattle, Washington, this 6th day of December, 1917.

GEORGE B. MORDEN.
